US0D1049632S

(12) **United States Design Patent** (10) Patent No.: **US D1,049,632 S**
(45) Date of Patent: ** Nov. 5, 2024

(54) **BAG WITH WHEELS**

- (71) Applicant: **DB Equipment AS**, Oslo (NO)
- (72) Inventors: **Truls Kristian Brataas**, Oslo (NO); **Hunter Nordhauser**, Oslo (NO); **Ida Nyborg**, Oslo (NO); **Benedicte Eggesvik**, Oslo (NO)
- (73) Assignee: **DB Equipment AS** (NO)
- (**) Term: **15 Years**
- (21) Appl. No.: **35/518,979**
- (22) Filed: **Oct. 24, 2023**

(80) **Hague Agreement Data**

- Int. Filing Date: **Oct. 24, 2023**
- Int. Reg. No.: **DM/232863**
- Int. Reg. Date: **Oct. 24, 2023**
- Int. Reg. Pub. Date: **Nov. 10, 2023**
